UNITED STATES PATENT OFFICE.

WILLIS C. JONES AND JOHN G. D. MACK, OF CINCINNATI, ASSIGNORS TO
THE BLACK & CLAWSON COMPANY, OF HAMILTON, OHIO.

PAPER-WINDING MACHINE.

SPECIFICATION forming part of Letters Patent No. 431,771, dated July 8, 1890.

Application filed August 22, 1889. Serial No. 321,653. (Model.)

To all whom it may concern:

Be it known that we, WILLIS C. JONES and JOHN G. D. MACK, of Cincinnati, Hamilton county, Ohio, have invented certain new and useful Improvements in Paper-Winding Machines, of which the following is a specification.

It is often desired in dealing with paper, and also with webs of other material, to take a roll of wide paper and to slit the wide web into two or more narrower webs, which are wound into independent rolls. Machines for accomplishing this generally consist of two or more winding-shafts, on which the narrower webs are wound, these shafts being revolved by power, the narrow webs winding upon these shafts and drawing their supply from the roll of wide paper, the separation of the wide web into narrower ones being effected by means of slitters acting on the paper between the single roll of wide paper and the several rolls of narrower paper. The paper will leave the wide roll as fast as it may be pulled off by the winding of the narrower rolls. The narrower rolls of paper increase in diameter as they receive paper, and consequently the peripheral speed of these narrower rolls, and also the speed of unwinding from the wide roll, increases as the winding progresses upon the narrower rolls. One of the narrower rolls may have a different diameter from that of any of the other narrower rolls, and as all must draw their supply of paper at the same speed from the single wide roll it follows that the velocity of rotation of the several narrower rolls must be related to each other inversely as the diameter of those rolls, and that this relationship is constantly changing. It has long been customary in the winding of paper and other webs in this manner to provide means by which the proper relationship between the velocity of the several narrow rolls becomes automatically adjusted. The means employed for effecting this adjustment have consisted in some cases of frictional driving devices and in other cases of surface-driven rolls, and in other cases of well-known equational boxes, and in other cases of self-adjusting idlers on the driving-belts. The equational box has long been employed where

two winders are to have their velocities interrelated to each other, one of the special merits of the equational box being that when one of the winders is entirely relieved from work, as by the accidental breakage of the web which it winds, the aggregate velocity of the several winders becomes concentrated into that idle-winder and the other winders cease revolving until the defect is remedied and the strain restored to the idle-winder. The equational box has also the merit of imposing equal strains upon the several winders where but two winders are used. Where more than two winders are employed, the equational box has been employed between each pair of winders and another equational box has been introduced between each pair of pairs of winders. By these means two or any geometrical ratio of two winders could be operated; but the equational box has never, so far as we are aware, been rendered operative in driving an odd number of winders under equal strain. When attempts have been made to drive an odd number of winders through an equational box, it has been found necessary to add an artificial resistance to one of the winders to make it balance the load represented by a greater number of winders opposed to it on the other side of the equational box.

By means of our invention we deal with any desired odd or even number of winders. We drive them through the medium of equational boxes. We operate all the winders at once, or we operate any number less than the whole without the necessity for imposing any artificial resistance upon any one of the running winders, whether the number running be odd or even.

Our invention will be readily understood from the following description, taken in connection with the accompanying drawings, in which—

Figure 1 is a plan of a paper-winding apparatus provided with three winding-shafts, one of these shaft H being illustrated as out of action and not in use; Fig. 2, a side elevation of the same; Fig. 3, a front elevation of the counter-shaft from which the winders are driven, this counter-shaft carrying three driven pulleys R, S, and T, the pulley R ap-

pearing in vertical section in the plane of line *a* of other figures, while the pulleys *S* and *T* expose vertical sections in the planes, respectively, of lines *b* and *c* of other figures; Fig. 4, a face view of the pulley *S* shown as detached from the counter-shaft; and Fig. 5, a plan similar to Fig. 1, but showing the three winding-shafts in use, the paper being slit into two slits and wound into three rolls instead of two, as in Fig. 1.

The construction of the machine illustrated is a mere exemplification of our invention.

In the drawings, *A* indicates the side frames of a paper-winding machine, the same serving for the support of sundry journal-boxes; *B*, the roll of wide paper mounted on the frame of the machine and adapted for free revolution as the paper is drawn off the roll; *C*, an ordinary pair of slitters engaging the wide web of paper after it leaves the roll *B* and serving to slit that wide web into narrower webs, this pair of slitters serving to exemplify any greater number of pairs of slitters which may be employed when it is desired to slit the wide web of paper into more than two narrow webs, the illustration of our invention assuming but two narrow webs of paper which are to be wound; *D*, one of the narrow webs of paper resulting from the action of the slitters; *E*, the other narrow web when the paper is to be made into two rolls only, as in Fig. 1; *E'*, the third narrow web when the paper is to be made into three rolls, as in Fig. 5; *F*, one of the winding-shafts on which one of the narrow webs of paper is to be wound; *G*, another similar winding-shaft on which the other narrow web is to be wound; *H*, another similar winding-shaft on which the third narrow web of paper would be wound in case we were dealing with three narrow webs instead of two, this winding-shaft being illustrated in Fig. 1 as out of action, but susceptible of being utilized whenever desired; *J*, the usual tail-shaft, one for each of the winding-shafts, these tail shafts representing the means ordinarily employed as a means for communicating motion to the winding-shafts, which are socketed to them in an ordinary manner; *K*, tail-shaft pulleys, one fast on each tail-shaft; *L*, a set-screw in one of the journal-boxes of the tail-shaft of winder *F*, this set-screw being adapted to engage its tail-shaft and lock it absolutely against rotation, the set-screw being a mere type of a device to be employed for preventing rotation of the tail-shaft and its winding-shaft; *M*, a precisely similar set-screw pertaining to the winder *G*; *N*, another similar set-screw pertaining to the winder *H*; *O*, a counter-shaft from which the tail-shafts are driven by means of separate belts engaging pulleys on the counter-shaft and on the tail-shafts, there being a separate belt for each tail-shaft, the counter-shaft in the exemplification being illustrated as disposed overhead, it being understood, of course, that any disposition of the counter-shaft is permissible which will

enable the proper motions to be transmitted to the winders; *P*, a receiving-pulley fast on the counter-shaft; *Q*, a belt to this pulley, by means of which rotary motion is given to the counter-shaft and thence to the winding system; *R*, a pulley loose on the counter-shaft and adapted to communicate by belt with the pulley *K*, pertaining to winder *F*; *S*, a similar pulley to similarly drive the winder *G*; *T*, a similar pulley to similarly drive the winder *H*; *U*, the belts by which the pulleys on the counter-shaft communicate motion to the several winders, that belt which engages the pulley *S* being a cross-belt by reason of the fact that the direction of rotation of the pulley *S* is opposite to that of the pulleys *R* and *T*, it being assumed that it will be the desire that all the winding-shafts revolve in the same direction; *V*, a bevel-gear fast on the counter-shaft alongside the pulley *T*; *W*, a planetary beveled gear loosely journaled in the pulley *T* and engaging the gear *V*; *X*, a bevel-gear loose on the counter-shaft between the pulleys *S* and *T* and engaging the gear *W*; *Y*, a gear loose on the counter-shaft and fast to gear *X*, the two gears *X* and *Y* being united back to back; *Z*, a planetary gear like gear *W*, but mounted in the pulley *S* and gearing with the gear *Y*; *a*, dotted lines indicating a section plane in the drawings, as hereinbefore mentioned; *b*, a similar line; *c*, a similar line; *d*, a bevel-gear loose on the counter-shaft and engaging gears *Z*; *e*, a bevel-gear united to gear *d*, gears *e* and *d* being in all respects similar to gears *Y* and *X*; *f*, a planetary gear like gear *W*, but mounted in pulley *R*; *g*, a bevel-gear fast on the counter-shaft like gear *V* and engaging planetary gear *f*; *h*, Fig. 3, an arrow indicating the direction of motion of receiving-pulley *P*, and consequently of the counter-shaft; *i*, arrows indicating the direction of motion of the pulleys *R* and *T*, and *j* an arrow indicating the direction of motion of pulley *S*.

The counter-shaft gives motion to all the pulleys in the direction of motion indicated normally at the same velocity of rotation. The effect is obviously to rotate all the winders uniformly; but those familiar with the qualities of the equational boxes involved will, upon an analysis, understand that the tendency of the device is to equalize the duty upon the several winders and so modify their velocities as to effect such equalization of duty. Assume now that, as illustrated in Fig. 1, we desire to use only the winders *F* *G*. We tighten the set-screw *N*, thus locking the tail-shaft of winder *H* absolutely against rotation. This also results in locking the pulley *T* against rotation. Turn now to Fig. 3, and imagine the pulley *T* locked against rotation, while the counter-shaft revolves in the direction of the arrow *h*. Pulleys *R* and *S* will revolve in the directions indicated by their arrows and will transmit motion to the winders *F* and *G* and will equalize the duty between them. On the same principle the counter-shaft may be pro-

vided with any desired odd number of pulleys, which may be employed in transmitting motion to a similar number of winding-shafts. The entire lot of winders may be used at once, 5 or any number of them desired may be locked out of action, leaving the others to be driven and used. It will at once be seen that the very principle of our invention abandons at once the apparently-established theory that 10 equational boxes must be made to deal with pairs or with pairs of pairs or that yielding artificial resistance must be imposed upon an odd winder to bring the duties into equilibrium.

15 We now proceed to a constructional analysis of the device illustrated in Fig. 3. The counter-shaft is a rotary one, and the terminal gears V and g are fast on the counter-shaft and revolve with it. The counter-shaft, so far 20 as its rotary quality is concerned, is therefore a mere expedient for giving rotation in the same direction and at equal speeds to these two gears. This motion of the two gears V and g may be produced in any other 25 way desired. In practice we have employed a non-rotary counter-shaft, and have driven the two gears V and g by two belts engaging pulleys secured directly to the gears which were then, of course, loose upon the counter- 30 shaft.

Assume now that, instead of using the three winders at once the winder F is not wanted, and that it becomes the duty of the counter-shaft to transmit motion only to the remaining 35 winders. In such case we tighten the set-screw L , Fig. 1, and thus lock the pulley R positively against rotation. The set-screw is thus merely a means for absolutely preventing the rotation of the pulley R , and any 40 means for accomplishing this result will answer. Turn now to Fig. 3 and analyze the device, on the assumption that pulley R is incapable of rotation. Gear g is revolving in the direction of arrow h , and, through the 45 medium of planetary gear f , having no longer a planetary motion, drives double gear d in a direction the reverse of arrow h , but at the same speed as the counter-shaft, the object being to get the desired effect upon the planetary wheel Z . Thus it will be seen that under 50 the conditions named the gears g , f , and d and the stationary pulley R constitute merely a means for getting rotary motion to the gear d at fundamental speed and in a direction 55 the reverse of that of gear V . When therefore less than the whole number of counter-shaft pulleys is to be employed in transmitting motion to the winders, it is only necessary to substitute for the idle counter-shaft 60 pulleys a means for properly rotating the bevel-gears, which engage the planetary gears of the pulleys which are actually employed. The idle-pulleys, locked against rotation and provided with their bevel-gears, furnish such

means. Obviously, if pulley R is not to be 65 used and the only office of it and its gears is to revolve the gear d in a certain direction at a certain definite speed, a belt-pulley secured to gear d and properly driven will answer the purpose in case permanent provision 70 is needed only for the employment of pulleys S and T .

It is to be understood, of course, that the counter-shaft pulleys and the tail-shaft pulleys and the belts engaging these pulleys are 75 mere mediums for transmitting rotary motion from the counter-shaft to the winders, and that spur-gearing or other equivalent transmitting mechanism might be employed.

We claim as our invention—

1. In a paper-winding machine, the combination, substantially as set forth, of an odd number of winding-shafts, a counter-shaft, a series of pulleys on the counter-shaft, consisting of one pulley for each of said winding-shafts, means for transmitting rotary motion from said pulleys to their respective winding-shafts, a planetary gear in each of said pulleys, united double gears between the contiguous pulleys of said series and engaging 85 the planetary gears thereof, a pair of driving-gears disposed one at each terminal pulley of the series and engaging the planetary gears thereof, and means for rotating both said driving-gears in the same direction at the same 90 speed.

2. In a paper-winding machine, the combination, substantially as set forth, of a number of winding-shafts, a counter-shaft, a series of pulleys on the counter-shaft, comprising a 100 pulley for each of said winding-shafts, means for transmitting rotary motion from said pulleys to said winding-shafts, a planetary gear carried by each of said pulleys, a united double gear between the contiguous pulleys of said 105 series and engaging the planetary gears thereof, a driving-gear engaging the planetary gear of each terminal pulley of the series, and means for rotating said two driving-gears at the same speed and in opposite directions to each other. 110

3. In a paper-winding machine, the combination, substantially as set forth, of a number of winders, a counter-shaft, a pulley upon 115 said counter-shaft for each of said winders, means for transmitting rotary motion from said pulleys to said winders, a planetary gear carried by each of said pulleys, united double gears disposed between contiguous pulleys and engaging the planetary gears thereof, driving-gears engaging the planetary gears of 120 the terminal pulleys of the series, and means for positively locking any of said counter-shaft pulleys against rotation.
